ATTORNEY

UNITED STATES PATENT OFFICE.

CHARLES K. MILLS, OF NEW YORK, N. Y.

DESIGN FOR AN ADVERTISING-BLANK.

SPECIFICATION forming part of Design No. 13,520, dated January 9, 1883.

Application filed November 24, 1882. Term of patent 3½ years.

To all whom it may concern:

Be it known that I, CHARLES K. MILLS, of the city, county, and State of New York, have invented a new and original Design for an Advertising or Ornamental Blank, of which the following is a full, clear, and exact description.

The nature of my design is fully shown in the accompanying pictorial representation, to which reference is made.

The object of my design is to furnish a novel configuration of parts for an advertising or ornamental blank; and it consists of an outline representation of a turtle, upon the back of which is arranged the representation of a human face (preferably a young girl's) and flowers.

Referring to the illustration, A represents the main part of my design, which represents the body or shell of a turtle, and which is provided with projections B B, C C, and D, illustrative, respectively, of the feet and head of the same. The body A and the projections B, C, and D produce together the representation of a turtle. Upon the body or shell A of the turtle is arranged a representation of a human face, preferably that of a pretty young girl, with a bonnet and flowers, as shown, whereby a very unique and ornamental effect of the design is obtained that is calculated to attract attention to its own characteristics as

well as to any advertising matter that may be marked, printed, impressed, or otherwise arranged thereon.

The representation of the turtle and of the human face may be colored or tinted with any appropriate color so as to correspond to a greater or less degree to the natural color of said turtle and face.

Having thus described my invention, I claim as new and desire to secure by Letters Patent—

1. The design for an advertising or ornamental blank, consisting essentially of the representation of a turtle having on its central portion or back the representation of a human face, substantially as shown and described.

2. The design for an advertising or ornamental blank, consisting of a main portion or body, A, representing the back of a turtle, projections B B, C C, and D, representing the feet and head of the same, and of the representation of a human face arranged on the main portion or body A, substantially as shown and described.

In testimony that I claim the foregoing as my invention I have signed it this 28th day of October, 1882.

CHARLES K. MILLS.
